UNITED STATES PATENT OFFICE.

HARRY KANTOR, OF RIMERSBURG, PENNSYLVANIA.

LAUNDRY HANGER.

Application filed January 6, 1923. Serial No. 611,058.

To all whom it may concern:

Be it known that I, HARRY KANTOR, a citizen of Hungary, residing at Rimersburg, in the county of Clarion and State of Pennsylvania, have invented certain new and useful Improvements in Laundry Hangers, of which the following is a specification.

This invention relates to certain new and useful improvements in laundry hangers and has particular reference to that type of hanger wherein a bracket member is hingedly supported upon the wall of a building adjacent a window opening with clothes line attaching means associated with the outer end thereof, the bracket hanger being retained in an inoperative position adjacent the wall of the building when out of use.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view of a laundry hanger constructed in accordance with the present invention, the same being illustrated as operatively positioned upon the wall of a building adjacent a window opening with a clothes line attached to the outer projecting end thereof,

Figure 2 is a top plan view of the hanger in its extended operative position, a portion of the building being shown in section with the hanger illustrated by dotted lines in its inoperative position,

Figure 3 is a fragmentary front elevational view of the hanger in its inoperative position,

Figure 4 is a detail sectional view taken on line IV—IV of Fig. 3 showing the spring clip carried by the building for retaining the hanger in its retracted inoperative position,

Figure 5 is a detail sectional view taken on line V—V of Fig. 3, and

Figure 6 is a detail sectional view taken on line VI—VI of Fig. 1.

Referring more in detail to the accompanying drawing, there is illustrated a laundry hanger in the form of a swingingly mounted bracket supported on the wall 1 of a building adjacent the window 2. The

laundry hanger embodies a fixed support including a bar 3 anchored as at 4 to the wall of the building adjacent the window 2, as clearly shown in Figs. 1 and 2, spaced forwardly directed arms 5 being carried by the bar 3 adjacent the upper and lower ends thereof and being suitably secured to said bar as indicated by the reference numeral 6 in Fig. 6.

The swinging member of the hanger includes a triangular frame having a horizontal rail 7, a vertical rail 8 secured as at 9 to the inner end of the horizontal rail, while an inclined brace 10 connects the upper end of the vertical rail 8 to the outer end of the horizontal rail 7 as shown in Fig. 1. The connection between the triangular frame and the bar 3 includes the formation of cylindrical sections 8^a in the rails 8 that are alined with the arms 5 to be inclosed by strap bearings 11 having the ends thereof secured as at 12 to the outer ends of the arms 5, permitting free swinging movement of the bracket frame on the bar 3.

A depending frame is suspended from the triangular frame, the same including a horizontal rail 13 having the upper end of a vertical rail 14 secured as at 15 to the outer end thereof, an inclined brace bar 16 extending between the lower end of the vertical rail 14 and the inner end of the horizontal rail 13. The connection between the two frames includes the formation of cylindrical sections 7^a at opposite ends of the horizontal rail 7 of the triangular frame that are enclosed by strap bearings 17 secured as at 18 to the horizontal rail 13 of the lower frame.

The lower end of the vertical rail 14 supports a pulley 19 over which a clothes line 20 is passed, and additional clothes suspending hooks 21 being secured to the inner end of the rail 13 as shown in Figs. 1 and 3. The two connected frames being suspended from the vertical bar 3, the same are maintained in a retracted inoperative position adjacent the wall 1 of the building as shown in Figs. 2 and 3 by a spring clip 22 attached to the wall and engaging the horizontal rail 7 as shown in Figs. 3 and 4, when the clothes line 20 is removed from the pulley 19.

From the above detail description of the device, it is believed that the construction and operation thereof will at once be apparent, it being noted that the hanger frames may be swung to a position in front of the window opening 2 to facilitate posi-

tioning of articles upon the clothes line 20. The hanger frames position the suspended clothes at a distance from the window opening 2 and the depending frame being swingingly mounted or suspended from the upper frame to permit limited movement thereof as well as the clothes line 20 to relieve the device of strains and the like. When out of use, the hanger frames are moved to a position adjacent the wall of the building 1 and are entirely positioned laterally of the window opening 2 and are so securely retained by the spring clip 22.

While there is herein shown and described the preferred embodiment of the present invention, it is nevertheless to be understood that minor changes may be made therein

without departing from the spirit and scope of the invention as claimed.

What is claimed as new is:—

In a laundry-hanger, a supporting bar, a triangular-shaped frame having a vertical rail, strap bearings carried by the supporting bar in which the vertical rail is journaled, a lower frame swingingly suspended from the triangular frame, and clothes line attaching means carried by the outer end of the lower frame, the connection between the two frames including bearing straps carried by the lower frame inclosing the adjacent rail of the upper frame.

In testimony whereof I affix my signature.

HARRY KANTOR.
